(57) **CLAIM**

The ornamental design for an electrical housing, as shown and described.

DESCRIPTION

FIG. 1 is a perspective view of an electrical housing showing a first embodiment of our new design;

FIG. 2 is a front view of the first embodiment of the electrical housing of FIG. 1;

FIG. 3 is a rear view of the first embodiment of the electrical housing of FIG. 1;

FIG. 4 is a top view of the first embodiment of the electrical housing of FIG. 1;

FIG. 5 is a bottom view of the first embodiment of the electrical housing of FIG. 1;

FIG. 6 is a right side view of the first embodiment of the electrical housing of FIG. 1; and,

FIG. 7 is a left side view of the first embodiment of the electrical housing of FIG. 1.

The broken lines depict unclaimed portions of the electrical housing and form no part of the claimed design.
